THE NATIONAL LITHOGRAPHING COMPANY,
WASHINGTON, D. C.

UNITED STATES PATENT OFFICE.

CHRISTIAN CHARLES ROES, OF BALTIMORE, MARYLAND, ASSIGNOR TO ROES BROTHERS, OF SAME PLACE.

DESIGN FOR A BREAD-LOAF.

SPECIFICATION forming part of Design No. 22,882, dated November 14, 1893.

Application filed September 12, 1893. Serial No. 485,363. Term of patent 3½ years.

To all whom it may concern:

Be it known that I, CHRISTIAN CHARLES ROES, a citizen of the United States, residing at Baltimore, in the State of Maryland, have invented and produced a new and original Design for a Bread-Loaf, of which the following is a specification.

The drawing shows a perspective view of the bread-loaf.

10 The design is for a rectangular single bread-loaf having vertical corrugations or flutes on its ends and sides. The loaf has angles, *a*;

the ends, *b*, and sides, *c*, are vertical and have a smooth crust-wall and corrugations or flutes, *e*, and the top, *d*, is rounded or convex.

What I claim is—

The design for a bread-loaf as herein shown and described.

In testimony whereof I affix my signature in the presence of two witnesses.

CHRISTIAN CHARLES ROES.

Witnesses:

CHARLES B. MANN, Jr.,
C. C. HINES.
